UNITED STATES PATENT OFFICE

91,593

DESIGN FOR A SKI

Roger W. Patten, Framingham, Mass.

Application August 18, 1933. Serial No. 49,053

Term of patent 7 years

To all whom it may concern:

Be it known that I, ROGER W. PATTEN, a citizen of the United States, residing at Framingham, in the county of Middlesex and State of Massachusetts, have invented a new, original, and ornamental Design for Skis, of which the following is a specification, reference being had to the accompanying drawing, forming a part hereof, in which:

Fig. 1 is a plan view and Fig. 2 a perspective view of a ski, showing my new design.

The essential feature of the design is the arrow on the forward part of the ski.

I claim:

The ornamental design for a ski, as shown and described.

ROGER W. PATTEN.
